(57) **CLAIM**

The ornamental design for an ice barrier device, as shown and described.

DESCRIPTION

FIG. 1 is an isometric view of an ice barrier device showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is a rear elevational view thereof; and,

FIG. 8 is another isometric view showing my design in an environment of use.

The glass shown in broken lines in FIG. 8 depicts environmental subject matter and forms no part of the claimed design.

1 Claim, 4 Drawing Sheets
